UNITED STATES PATENT OFFICE.

FRANK HOFFMAN, OF DUNKIRK, NEW YORK, ASSIGNOR OF ONE-HALF TO EDWIN K. BUTTOLPH, OF DUNKIRK, NEW YORK.

BRAKE-GEAR.

1,191,107.

Specification of Letters Patent.

Patented July 11, 1916.

Application filed November 19, 1914. Serial No. 372,984.

To all whom it may concern:

Be it known that I, FRANK HOFFMAN, a citizen of the United States, residing at Dunkirk, in the county of Chautauqua and State of New York, have invented certain new and useful Improvements in Brake-Gear; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to brake-gear and has for its object the construction of brake-operating gear whereby the strains upon the upper and lower halves of a brake-band will at all times be equalized, and whereby the 20 braking resistance will be the same whether the brake-drum is revolved forward or backward.

The features of my invention are herein-after fully explained and pointed out, and 25 are illustrated in the accompanying drawings, in which:

Figure 1, is a side elevation of the same showing the operating pinion in section. Fig. 2, is an edgewise elevation of the same. 30 Fig. 3, is a section of a brake-drum on the line $x-x$ looking in the direction of the arrow in Fig. 4, showing my invention as applied to an internal brake. Fig. 4, is a vertical section of the same on the line $y-y$ 35 in Fig. 3, looking in the direction of the arrow.

In these drawings A, indicates a brake-drum flange; A', indicates a wheel-hub upon which the drum flange A, is secured; B, 40 indicates a brake-band in which there is secured suitable friction material B'. Secured on one end of the band B, is a pair of plates C C, in spaced relation to each other, each of said plates C C, having a segmental 45 opening C', therethrough. Upon one side of said opening C', in each of said plates, I provide a rack of gear-teeth c. The gear-teeth c, are preferably formed in the openings C', of the plates C C, nearest to the 50 brake-band B. Upon the opposite end of the brake-band B, I secure a plate D, adapted to slide between the plates C C. The plate D, is provided with a segmental opening D', 55 therethrough similar to the opening C', in the plates C C, and in one side, preferably

the side farthest from the brake-band B, of the opening D', I provide a rack of gear-teeth d. Transversely through the openings C' and D' in the plates C C and D, I place a gear-pinion E, the teeth of which intermesh with the gear-teeth c and d, of the plates C C and D.

The pinion E, is provided with a collar E', (see Fig. 2) on one end thereof, and with a lever F, on the other end, which lever F, has a hub f. The lever F, is preferably secured in place by a nut F', or other suitable means to retain it in place on the pinion E. The collars E' and F', serve to retain the pinion E, in place in the openings C' and D', in the plates C C and D. Now, when power is applied to the lever F, the pinion E, is rotated thereby, which operates to contract the brake-band B.

For supporting the brake-band B, out of contact with the drum A, when the band is open, as shown in Fig. 1, I provide a supporting loop G, which is secured to the brake-band B, and mounted on the housing H, is an arm H', the end of which extends laterally through the loop G, and thereby supports the brake-band B. I also secure a bracket H², upon the housing H, which extends over an ear h, on the brake-band B; and through an opening in the bracket H², I pass a bolt H³, which enters a screw threaded opening in the ear h, and upon the bolt H³, above the bracket H², I place a spring h', so that the brake-band B, is always supported out of contact with the brake-drum flange A, when the brake is open as shown in Fig. 1. In Fig. 1, I have shown the pinion E, as being hollow, so that if desired a supporting pin (not shown) may be placed therein, from which that side of the brake-band may be supported, instead of from the ear h. When the lining B', of the band B, has become worn, it is easy to re-adjust the band closer to the drum by removing the pinion E, and slightly moving the plates C C and D, so that they will overlap each other farther and then replacing the pinion.

In Figs. 3 and 4, I have shown my invention embodied in an internal or expanding brake, in which the plates are operated by the pinion E, to expand the brake-band against the interior wall of the brake-drum flange A.

In Figs. 3 and 4, the lever F, is mounted upon a stud-shaft F', which is journaled in

the housing H; and inside of the housing H, I secure on said stud-shaft a lever e. Upon the pinion E, I secure a lever e', and I connect the levers e and e' by means of a link e² so that power, when applied to the lever F, is communicated to the pinion E, through the levers e e', and link e². For supporting the internal band B, out of contact with the flange A, I secure a loop G' thereon, which is engaged by a stud G², secured on the housing H, and I provide springs g g, which are attached to loops b b, on the brake-band B, and to the stud-bolt F', the operation of which springs is to cause said brake-band to move away from the flange A, when the lever F, is released.

Having thus shown and described the construction of my improved brake-gear, it is believed the operation thereof is so obvious that further description thereof is unnecessary.

Therefore what I claim as new and desire to secure by Letters-Patent is:

1. In a friction brake-gear, an open brake band, spaced slotted plates secured on one end of said brake-band, internal rack teeth in the side of the slots of said bars adjacent to said brake-band, a slotted plate secured

to the opposite end of said brake-band, internal rack teeth in the side of the slot of 30 said bar, farthest from said brake-band and a pinion in said slots intermeshing with said internal rack teeth and engaging the sides of the slots in said plates opposite said rack-teeth, substantially as set forth. 35

2. In a brake-gear, a drum, a brake-band partially inclosing said drum, gear-racks secured on each end of said band and overlapping each other, a gear-pinion between said gear-racks and intermeshing therewith and supported thereby, means to rotate said pinion, an arm rigidly supported with reference to the axis of said drum, means on said brake-band engaging said arm to support one side of said brake-band, another arm 45 rigidly supported with reference to the axis of said drum, and an elastic connection between said arm and said brake-band, substantially as set forth.

In testimony whereof I affix my signature, 50 in presence of two witnesses:

FRANK HOFFMAN.

Witnesses:

ELTON D. WARNER,
IRENE E. MORRISON.
